UNITED STATES PATENT OFFICE.

THOMAS B. DRAPER, OF OAKLAND, CALIFORNIA.

COMBINATION TABLE AND BED.

1,375,449.

Specification of Letters Patent. Patented Apr. 19, 1921.

Application filed October 24, 1918. Serial No. 259,517.

To all whom it may concern:

Be it known that I, THOMAS B. DRAPER, a subject of the King of England, residing at Oakland, in the county of Alameda and State of California, have invented new and useful Improvements in Combination Tables and Beds, of which the following is a specification.

This invention relates to convertible furniture and particularly pertains to a combined table and bed. It is the principal object of this invention to provide an article of furniture which will perform the double function of providing a table of artistic appearance under normal conditions and thereafter being capable of conversion to produce a full-sized bed of dimensions suitable for accommodating two persons, said bed and table being both rigid in their construction and not intimating in any way their convertible nature when in any position, and further providing improvements over the structure shown in my co-pending application, entitled "Combination table and bed," filed October 22, 1917, and bearing the Serial Number 197,776.

It is another object of this invention to provide a structure as above specified, within which a complete set of springs, mattress and bed clothing may be folded and which will be automatically unfolded as the bed is made, said mattress being detachably secured to the frame of the bed springs and thus being held in proper shape at all times.

Other objects of the invention will appear hereinafter.

The invention is illustrated in the accompanying drawings in which—

Figure 1 is a view in plan as seen on the line 1—1 of Fig. 2 and as particularly disclosing the disposition of the bed springs when folded within the table.

Fig. 2 is a view in transverse section as seen on the line 2—2 of Fig. 1, further disclosing the folded position of the springs, mattress and bed clothing within the table.

Figs. 3 and 4 are fragmentary views in elevation, illustrating the articulate construction of the spring frames.

Fig. 5 is a view in vertical section, showing the manner in which the spring frame is supported within the bed and the manner in which the helical tension springs are supported.

Fig. 6 is a fragmentary view in perspec-

tive, illustrating the detachable connection between the mattress and the spring frame.

Fig. 7 is a view in section and elevation, disclosing the bed as folded within the table and particularly illustrating the relation of the head, foot and springs to the table when folded.

Fig. 8 is a fragmentary view in end elevation showing the folded table.

Fig. 9 is a view in perspective, disclosing the latch for the spring frame.

Fig. 10 is a view in side elevation showing the completely made bed.

Fig. 11 is a view in side elevation showing the bed with parts broken away to more clearly disclose the manner in which the opposite ends of the spring frame are supported.

Referring more particularly to the drawings, 10 indicates a table top shown as 75 formed in one piece and being provided with aprons 11, 12 and 13. The apron 11 is constructed to give the appearance of a drawer and is therefore provided with knobs 14. These knobs extend outwardly, 80 having spherical faces which form casters, as particularly shown in Figs. 10 and 11. The structure comprising the end apron 11 and the two side aprons 12 and 13 is rigidly connected with a set of table legs 15. These 85 legs extend vertically at the opposite ends of the apron 11 and are connected by hinges 16 to cross-rails 17.

The aprons 12 and 13, as clearly shown in Fig. 1, do not extend the entire length of 90 the table top but terminate substantially at the center thereof. From this point complementary apron members 18 and 19 are provided to complete the sides of the table. A front apron 20 is united with these last 95 named side aprons and corresponds to the opposite apron 11. This board is also fitted with the knobs 14, which give it the appearance of a false drawer. The structure thus formed extends beneath the overlapping table top and is supported upon legs 21, one of which is fixed at each end of the board 20. These legs are united with hinges 16 to the opposite ends of the cross-rails 17. Thus it will be seen that the pairs of legs 100 15 and 21 may swing outwardly and downwardly from the cross-rails 17 by reason of their hinges 16 and may thereafter assume positions in horizontal alinement, as shown in Fig. 10. To facilitate in this operation, 105

Fig. 6 is a fragmentary view in perspec-

specially formed casters 22 are provided. These casters are fixed to the lower ends of the several legs and have arms extending outwardly parallel to each other and to support 5 rollers, the circumferential faces of which will at all times be outside of the opposite outer corners of the legs, thus providing a roller bearing for the legs as they swing.

10 The cross-rails 17 are united longitudinally of the table by means of a book-shelf 23. This shelf is secured between the opposing faces of the rails and thus holds them rigidly together. Extending upwardly from each of the cross-rails 17 and spaced in relation to each other, are a pair of posts 25 and 26. These posts are rigidly connected at their upper ends by lattice work which not only proves ornamental but secures them in fixed relation to each other and provides a rigid support for a spring 15 cross-frame member 27 directly supported by the posts. The posts 25 and 26 at the opposite ends of the table are also connected by rails 28. This will form a stable sub-structure upon which the springs of the bed may be mounted. Each end of the table is fitted with one of the spring cross-frame members which has preferably been constructed of angle-iron, bent as shown in 20 Fig. 7. These members extend upwardly from the center of the table and terminate at points slightly within the inclosure made by the aprons 11 and 20. Frame sections 25 29 and 30 are pivotally secured by pins 31 to the opposite ends of the members 27. These sections are again secured by pins 32 to the outer ends of end spring frame sections 33 and 34. The sections 29 and 33 30 are adapted to form the head of the bed while the longer sections 34 and the section 30 form the foot of the bed. These four sections unite with the rigid central sections 27 to provide a complete bed structure.

40 45 The free ends of the sections 33 and 34 are rigidly connected by cross-frame members 35 and 36 respectively. These two cross-rails stand in horizontal alignment when the springs are unfolded and due to the inclination of the various sections from the center of the rigid frame members 27, it will be seen that the side rails of the bed will be lower than the end rails and therefore will insure that the center of the 50 springs will be higher than the sides so that weight disposed upon the springs will bring them to a level transversely.

The springs may be of any desired construction and are here shown as formed of 60 cushion wire appropriately connected with the end rails 35 and 36 by tension springs. It will be observed that the frame members 33 are shorter than the members 34. This has been done to permit the members 33 and 65 34 to lie in the same horizontal plane when

folded, as shown in Fig. 7. For this reason a head board 37 must be provided and this board is rigidly fixed to the end of each of the members 33, and when the springs are folded, extends beneath the overlapping 70 end of the frame members 34. When the bed is unfolded, the head board will extend outwardly and will rest upon supporting stops 38, carried on the underface of the table top which will at that time constitute 75 the head of the bed. The support for the opposite end of the spring frames consists of extension boards 39 secured upon the inner faces of the side aprons 18 and 19 and normally overlapping the inner faces 80 of the aprons 12 and 13, as shown in Fig. 1. These members carry brackets 40 upon which guide pins 41 are fixed. The guide pins extend inwardly through longitudinal slots 42 formed through the sides of the 85 frame members 34 and adjacent the outer ends thereof, as shown in Fig. 11. When the bed is formed, these pins support this part of the frame and conclude the bed structure.

90 Referring particularly to Figs. 3 and 4, it will be seen that the various frame sections of the springs are arranged in abutting relation to each other and that they are connected by side links 43 which are 95 riveted to the pivot pins of the frame. This construction will insure that the side rails will be as one continuous piece and when unfolded will assume a rigid longitudinal alined position in relation to each other. 100 The end rails 35 and 36 of the frame are formed with a series of slots 45 which are distributed throughout their length and are provided to receive fastening members 46. These members may be turned to pass 105 through the slots and thereafter adjusted to become locked thereover. These fasteners are secured to end strips 47 incorporated within the construction of a mattress 48. By means of the fasteners as distributed 110 along the opposite ends of the mattress, this member may be held in proper relation to the spring frame irrespective of whether it is folded or unfolded. The construction is especially convenient during the folding of 115 the springs as it insures that the ends of the mattress will lie in their proper position after the table top has concealed them.

120 As a means for binding the mattress and bed clothing within the springs and insuring that they will be held compactly to permit folding of the table, a series of strapping links are provided. This structure comprises links 49 pivotally secured to the opposite end rails of the springs and distributed there along as shown in Fig. 1. Each of these links is pivotally connected to an angle link 50 which in turn is rigidly secured to rock bars 51. These last named 125 bars are pivoted between the posts 25 and 130

26 of the sub-frame structure. The angle members 50 are formed so that they will properly circumscribe the under-face and outer sides of the folding mattress, as shown 5 in Fig. 2. The links 49 will thereafter extend over the free ends of the springs and mattress and will coöperate with the members 50 to bind the mattress and bed clothing in proper condition to allow the table 10 top to fold down. Lifting of the head portion of the bed is assisted by tension springs 52 which extend from points 31 upon the rigid frame members 27 to the outer edge of the table top. These springs also will 15 cushion the downward movement of the top and act to counterbalance its weight so that the members will not fall upon the floor. The spring 52 passes over an idler roller 53 which permits it to move freely 20 and to contract and expand as desired. The opposite end of this spring is fastened at a point upon the frame member 34 and will thus act to hold this frame member in its closed position when folded and to assist in 25 holding it rigidly in its open position when unfolded. When the springs are folded, they are fastened together by means of a wire loop 54 which is pivoted to one of the end rails of the frame and extends through 30 a second loop 55, clearly shown in Fig. 9.

Normally the upper portion of the table is disposed, as shown in Fig. 8 and has the appearance of being a solid top table having drawers on the opposite sides thereof 35 with a rack beneath for receiving books and magazines. When it is desired to convert the table for use as a bed, the table top is grasped along the side above the apron 20 and is swung upwardly and away therefrom. This swinging action is accommodated by the hinges 16, which will permit the lower ends of the legs 15 to swing under the transverse bars 17 and to assume the position shown in Figs. 10 and 11. When 40 the knobs 14 rest upon the floor, the table leg will be horizontal and supported upon the rollers of the casters 22 and the face of the knobs. In this position, the table top will stand perpendicularly and the side 45 aprons 12 and 13 will act to form part of a bed head. The legs 22 may then be swung downwardly into a horizontally alined position in relation to the legs 15 and will thus lower the transverse braces 17 to rest directly upon the upper faces of the legs. This, of course, will drop the entire center 55 of the table and will cause the spring frame members 27 to be disposed at a proper bed height. During the downwardly swinging 60 movement of the legs 21, the frame portions 34 will be swung outwardly and downwardly, as drawn by the pins 41. These pins will pass along the slots 42 and will thus support the foot portion of the springs 65 in their unfolded positions. The upper end

of the bed springs may then be unfolded and the head board brought to rest upon the supporting stops 38. When the bed is thus unfolded the mattress will assume a substantially horizontal position, as shown 70 in Figs. 10 and 11 and if bed clothing has been previously placed upon the mattress, the entire outfit will be in condition for use. In the event that it is desired to remove the mattress or reverse it, the catch-members 75 46 may be released from the ends of the spring frame through the slots 45 and the mattress manipulated as desired. The bed may be closed by a reversal of the previously described operation and will then 80 serve all the purposes of a substantial table.

It will thus be seen that the bed structure here disclosed, while simple and substantial in its construction, provides desirable means for utilizing an article of furniture as a bed 85 or table and in either case causing the article to appear substantial and sightly.

While I have shown the preferred form of my invention, it will be understood that various changes in the combination, construction and arrangement of parts may be made by those skilled in the art, without departing from the spirit of the invention 90 as claimed.

Having thus described my invention, what 95 I claim and desire to secure by Letters Patent is—

1. An article of furniture having a top, legs, one of which is disposed beneath each of the corners of the top and to one set of 100 which the top is fixed, cross-braces to which the legs are pivotally secured, an articulately constructed spring frame supported from and above said cross-braces directly beneath the table top and normally concealed by the table top and means whereby the legs may be swung outwardly and downwardly to completely expose the springs and to lower them to the height of an ordinary bed. 105

2. An article of furniture having a top, legs, one of which is disposed beneath each of the corners of the top and to one set of which the top is fixed to form a head board when unfolded, cross-braces to the ends of 110 which the legs are pivotally secured, an articulately constructed spring frame supported by said cross-braces and normally folded beneath and concealed by the table top and means whereby the legs may be 115 swung outwardly and downwardly to completely expose the springs and to lower them to a bed height, and means whereby the springs may be unfolded to extend in a substantially horizontal plane. 120

3. An article of furniture having a top, legs, one of which is disposed beneath each of the corners of the top and to one set of which the top is fixed, a center structure at the bottom of which the legs are pivotally 125 supported. 130

secured, an articulately constructed spring frame supported on top of the center structure and normally concealed by the table top, means whereby the legs may be swung outwardly and downwardly to completely expose the bed springs and to lower them to a bed height and springs secured to the center section and the opposite ends of the spring-frame for facilitating in the movement of said legs.

4. In a table, pairs of legs, braces having their opposite ends hinged to said legs, a table top secured to one set of legs and normally resting with its opposite edge upon the opposite set of legs, a frame structure carried upon the braces, an articulate bed spring frame secured upon said last named structure, means whereby the sets of legs may be swung outwardly and downwardly in opposite directions simultaneous with the swinging of the table top to form the head and foot of a bed, means carried by said oppositely swinging portions for supporting the head and foot of the bed springs and means for counterbalancing the weight of the swinging members during their operation.

5. An article of furniture having a horizontal plane top, legs disposed under the four corners thereof, two of which are secured to said top, cross-braces extending horizontally from each of the legs connected with the top and connecting at their opposite ends with the other legs, means whereby said legs may be swung outwardly and downwardly to form a bed structure, roller means carried by the legs adapted to provide constant supports therefor throughout their range of movement, and knobs carried by the opposite sides of the swinging structures adapted to form supporting feet therefor when they have been swung to their lowermost positions.

6. An article of furniture comprising a set of legs adapted to support a table top, a pair of cross-braces one of which is disposed between each pair of legs near the lower ends thereof, a bed spring frame disposed above said braces and supported thereby, said frame having side rails which slightly incline upwardly from their longitudinal center, hinge connecting means between the ends of said cross-braces and legs whereby the legs are permitted to be swung outwardly and downwardly to form a support for the spring frame and means supporting said legs when unfolded so that each leg will be disposed substantially parallel with the corresponding inclined section of the side rails whereby a uniform bed structure is had when unfolded.

7. An article of furniture comprising a top portion, sets of legs, one set of which is permanently secured to said top portion, a central brace structure hinged at its oppo-

site side to the legs of said set, a foldable bed-frame normally concealed by the table top and permanently secured at the top of the said brace structure, and means connecting the lower end of said bed-frame with one set of legs whereby downward and outward swinging movement of the legs will cause the bed-frame to be drawn outwardly to assume the horizontal position.

8. An article of furniture having a top, pairs of legs, one pair of which is permanently secured to the top and the other pair upon which the top is adapted to rest, panels securing the legs of each pair in permanent relation to each other, a central brace structure to the opposite sides of which the legs are hinged at points near their feet and a jointed spring frame supported upon the top of said base structure and adapted to assume a rectangular position when folded and to be extended outwardly into a horizontal plane across the top of the supporting structure when the legs of the table are swung outwardly to their unfolded position.

9. In a table sets of legs, cross panels securing the legs of each set in fixed relation to each other, side frame members fixed to the legs and adapted to normally stand in horizontal alinement and abutting each other, a cross-frame structure normally disposed between the legs and to which they are pivoted, a table top fixed to one set of legs and adapted to rest upon the other set of legs when the table is folded, a foldable bed-spring frame carried by the cross-supports to be normally folded and concealed beneath the table top and by the panels and side-frame members, and means connecting one end of said bed-frame with the side panels of one set of legs whereby the outward and downward swinging of said legs will cause one end of the bed-frame to be automatically unfolded.

10. An article of furniture comprising a central brace section, a pair of legs hinged to the opposite sides of said brace section and normally standing parallel and vertical, side panels connecting the legs of each pair and panels carried by the legs and adapted to abut against each other when in horizontal position, a table top carried by one set of legs and adapted to be partially supported upon the other set, a central brace structure to the lower end of which the legs are hinged, the upper end of said structure projecting into the compartment formed by the side and end panels, a jointed sectional bed-frame carried by said supporting structure and normally folded to assume a rectangular position, beneath the table-top and concealed by the surrounding panels, and means whereby the table-top and one set of legs may be swung in one direction and the other set of legs in the other to conceal and unfold the bed-frame and to permit the

opposite ends of said frame to be supported in a horizontal plane whereby a bed will be formed.

11. An article of furniture comprising a central brace section, a pair of legs hinged to the opposite sides of said brace section and normally standing parallel and vertical, side panels connecting the legs of each pair, end panels carried by the legs and adapted to abut against each other when in horizontal position, a table top carried by one set of legs and adapted to be partially supported upon the other set, a central brace structure to the lower end of which the legs are hinged, the upper end of said structure projecting into the compartment formed by the side and end panels, a jointed sectional bed frame carried by said supporting structure and normally folded to assume a rectangular position beneath the table top and concealed by the surrounding panels and means whereby the table top and one set of legs may be swung in one direction and the other set of legs in the other to conceal and unfold the bed-frame and to permit the opposite ends of said frame to be supported in a horizontal plane, whereby a bed will be formed, and spring members secured by their one end to the supporting structure and by their other ends to the jointed sections of the bed-frame whereby they will facilitate in closing said frame.

12. In a device of the character described, a sectional and foldable bed spring supporting frame, a central support therefor and means for binding the sections and springs in their folded positions simultaneously with the folding thereof.

13. An article of furniture comprising a set of legs adapted to support a table top, a pair of cross-braces one of which is disposed between each pair of legs near the lower ends thereof, and hinge connections between the ends of said braces and legs, a foldable bed frame disposed above the cross-braces and supported thereby, said bed frame comprising two end sections and an intermediate section, said sections when unfolded extending slightly upwardly from the longitudinal center of the intermediate section and said legs being adapted to be swung outwardly and downwardly in position for supporting said bed frame when unfolded and means for supporting the ends of said legs so that each leg will be substantially in parallelism with the corresponding section of the bed frame.

14. An article of furniture comprising separable leg units, each consisting of a pair of legs permanently secured together by cross-panels and provided with parallel end panels, the end-panels of each set of legs being adapted to abut against each other when in their folded position, a table top secured to one set of legs with its panels

and adapted to rest upon the opposite set of legs with its panels, a brace structure, the upper end of which projects into the compartment formed by the panels, at the lower end of which terminates a short distance from the floor line where it is hinged to each of the legs and casters secured upon the legs and adapted to extend outwardly beyond the vertical side faces of said legs, whereby the lower ends of the legs will be supported above the floor line at all times during the swinging of the section.

15. In a device of the character described a supporting structure, a bed-frame section fixed to the top of said structure, a pair of short bed-frame sections hinged at the opposite ends of said central section, a pair of end sections hinged at the other ends of said short sections and adapted to be folded over into parallel relation with the first named section, and with the ends adjacent to each other and a plurality of articulate binding members secured by their one end to the supporting structure and by their opposite ends to the ends of the bed frame whereby a movement of the frame to its folded position will cause said binding members to be drawn around the frame and thus hold the springs and bed clothing carried thereby in a compact manner.

16. In a device of the character described a sectional and foldable bed spring supporting frame and a central support therefor, and foldable links connected between each end of the foldable spring frame and the central support, whereby the springs and frame sections are bound into their folded position simultaneously with the folding thereof.

17. In foldable furniture of the class described, a sectional bed spring supporting frame comprising a central section and two sections beyond each end of the central section, said sections being foldable into a form rectangular in cross-section, a support for the central section and foldable links connected between each end of the foldable spring frame and the central support, whereby the springs and frame sections are bound into their folded positions simultaneously with the folding thereof.

18. In foldable furniture of the class described, a sectional bed spring supporting frame comprising a central section and two sections beyond each end of the central section, said sections being foldable into a form rectangular in cross-section, a support for the central section and foldable links connected between each end of the foldable spring frame and the central support, whereby the springs and frame sections are bound into their folded positions simultaneously with the folding thereof, a U-shaped member having its legs rigidly secured to the forward end of one end section, and a

- second U-shaped member having its legs pivotally secured to the end of the other end frame section, said U-shaped member being adapted to lock said bed spring and frame in folded position, and also adapted to draw the two end sections of the frame members toward each other and thus further bind the foldable links about the bed spring and frame sections.
- 10 19. In a device of the character described, a sectional bed spring supporting frame comprising a central section and two sections beyond each end of the central section, said sections being foldable into a frame 15 rectangular in cross-section, a support for the central section and means between each outer end section and the support for the central section, whereby the springs and sections will be bound together simultaneously with their folding, said means between each end frame section and support comprising a pair of links having one of their ends pivotally secured to each other and their opposite ends pivotally connected 20 to the end frame section and support, and the lowermost of said links being angular in shape, so that when the links are brought to their binding position, said lowermost link will serve as a binder for the lower side of 25 the folded frames and its vertical side, and said upper links forming the binder for the upper side of the folded sectional frame and springs.
20. In a device of the character described, a sectional bed spring supporting frame comprising a central section and two sec-

tions beyond each end of the central section, said sections being foldable into a frame 30 rectangular in cross-section, a support for the central section and means between each outer end section and the support for the central section, whereby the springs and sections will be bound together simultaneously with their folding, said means between each end frame section and support 35 comprising a pair of links having one of their ends pivotally secured to each other and their opposite ends pivotally connected to the end frame section and support, and the lowermost of said links being angular in shape, so that when the links are brought to their binding position, said lowermost link will serve as a binder for the lower side of 40 the folded frames and its vertical side, and said upper links forming the binder for the upper side of the folded sectional frame and springs.

In testimony whereof I have hereunto set 50 my hand in the presence of two subscribing witnesses.

THOMAS B. DRAPER.
